UNITED STATES PATENT OFFICE.

AVERY E. KEELY, OF HUNTINGTON PARK, CALIFORNIA, ASSIGNOR OF ONE-HALF TO
I. G. KRIEGER.

GAME APPARATUS.

Application filed April 10, 1924. Serial No. 705,536.

To all whom it may concern:

Be it known that I, AVERY E. KEELY, a citizen of the United States, residing at Huntington Park, in the county of Los Angeles and State of California, have invented certain new and useful Improvements in Game Apparatus, of which the following is a specification.

This invention relates to game apparatus and it consists in the novel features herein-
10 after described and claimed.

An object of the invention is to provide apparatus adapted to be used by two or more contesting players to carry out a game involving the exercise of the faculties of skill and judgment and simulating the various plays which may be made in the progress of a game of base ball in order that interest may be instilled in the game during the
20 progress thereof.

With this object in view, the apparatus includes a mat or board laid off in the form of a field having a diamond at the center thereof with the usual bases and plates indicated at the corners thereof. The marginal area of the field may be used for retaining and supporting pieces which represent the players. The apparatus also includes disk-shaped pieces having the names of contesting teams or sides, inscribed thereon. The apparatus also includes two sets of cubical pieces of different colors. The unit of one set of the last mentioned cubical pieces being provided at its sides with inscription indicating the plays which may be made by a batter or base runner and the sides of the unit of the other set of cubical pieces being provided with inscriptions indicating the plays which may be made by the batters and fielders in a base ball game.
40

In the accompanying drawing:

Figure 1 is a plan view of the board or mat used in the game apparatus.

Figure 2 is a perspective view of a disk piece used in the apparatus and which is distinguished by bearing the name of a certain team.
45

Figure 3 is a similar view of another similar piece but of a different color from that piece illustrated in Figure 2 and bearing the name of another base ball team.
50

Figure 4 is a perspective view of a cubical piece used in the apparatus and having upon its sides inscriptions indicating the plays which might be made by a base runner,
55

Figure 5 is a similar view of another cubical piece having upon its sides inscriptions indicating the plays which might be made by a batter,

Figure 6 is a perspective view of a cubical piece having upon its sides inscriptions indicating the plays which might be made by a base runner.
60

Figure 7 is a perspective view of still another cubical piece having upon its sides inscriptions indicating the plays which might be made by a pitcher.
65

As illustrated in the accompanying drawing, the game apparatus includes a board or mat 1 having at the center thereof a position 2, which represents the pitcher's box. A diamond 3 is laid off upon the obverse surface of the board or mat 1 and surrounds the pitcher's box 2. Plates 4 are indicated at the corners of the diamond 3 which are aligned with the median longitudinal dimension of the board or field 1. Bases 5 are indicated at the corners of the diamond 3 which lie between the plates 4. Benches 6 are indicated at the opposite diagonal corners of the board 1 and upon these benches the pieces representing the players may be deposited at the beginning of the game. Benches 7 are indicated at the other opposite diagonal corners of the board 1 and upon the said benches the pieces which have scored may be deposited during the progress of the game. The benches 6 and 7 at one end of the board are of the same color and of a color different from the benches at the opposite end of the board 1. The benches at the same end portion of the board are of the same color. The game apparatus also includes one or more disks 8 which are colored red and which simulate the cover of a base ball and which are provided at their central portions with the name of a team. The apparatus also includes one or more disk pieces 9 which are colored yellow, and resemble a base ball and which are provided at their intermediate portions with the name of another base ball team.
80

The game apparatus also includes one or more cubical pieces 10 which are colored red and which bear upon their side surfaces inscriptions indicating the plays which may be made by a base runner.
100

The game apparatus also includes one or more cubical pieces 11 which are also colored red and which bear upon their sides inscrip-
105
110

tions indicating the plays which may be made by a batter. The game apparatus also includes one or more cubical pieces 12 which are colored yellow and which bear upon their sides inscriptions indicating the plays which may be made by a base runner. The game apparatus also includes one or more cubical pieces 13 bearing upon their sides inscriptions indicating the plays which may be made by a pitcher during the progress of a game of base ball.

In carrying out the game various rules may be prescribed, but in general, the rules which apply to the standard game of base ball are applicable to the various plays which may be made by the individuals of the contesting games. In carrying out the game one player stands at one end of the board or mat 1 and the other player at the opposite end. The player who represents the side which is in the field places his disk 8 or 9 as the case may be, in the pitcher's box 2. The contestants in the game assemble their pieces upon the players' benches 6. The player who represents the side which is at the bat casts his cubical block or blocks upon the marginal portion of the field and the inscription upon the side or sides thereof which turn up indicate the play or plays which are to be made by the batter or base runners. The contestant who represents the side which is in the field casts his cubical block or blocks and the inscriptions which appear upon the uppermost surfaces of the said block or blocks indicate the play or plays which have been made by the batter or fielders. As the players make the round of the diamond and score, they are positioned upon the scorers' benches 7 and consequently the pieces which are accumulated upon these benches indicate the scores which have been made by the contesting sides. The players which out at bat or while running the bases are retired to the players' benches 6.

From the above description taken in con-

junction with the accompanying drawing, it will be seen that apparatus of simple and durable character is provided and which may be used for exercising skill and judgment in carrying out in imitation the progress of a game of contested base ball. The pieces which are used for indicating the various players are also used for keeping the scores and the diamond is so arranged upon the field that the plate at either of the corners of the diamond which is located in alignment with the median longitudinal dimension of the field may be used as a home plate and while all of the players will move around the diamond in the same direction, the home plate for one team is at one corner of the diamond while the home plate for the other contesting team is at the opposite diagonal corner of the diamond.

Having described the invention, what is claimed is:—

A game apparatus comprising a board having a surface representing a field, a station laid off at the center of the field and representing a pitcher's box, a diamond surrounding the pitcher's box and provided at its corners with indications representing bases and plates, the plates being diagonally opposite each other and the bases located between the plates, the field being provided at its marginal portions with areas indicating benches, disk shaped pieces of different colors and bearing upon their obverse sides the names of different contesting teams, said pieces adapted to be deposited upon the benches, the plates and the bases, and cubical pieces one of them having upon its sides inscriptions representing the plays which may be made by a batter, and others the plays which may be made by a player at the bat, another of plays which may be made by a base runner, and still another having at its sides inscriptions indicating plays which may be made by a pitcher.

In testimony whereof I affix my signature.

AVERY E. KEELLY.
